UNITED STATES PATENT OFFICE.

PHILIPP WIRTH, OF NEW YORK, N. Y.

FILLING-FAUCET.

1,338,662.

Specification of Letters Patent. Patented Apr. 27, 1920.

Application filed June 18, 1918. Serial No. 240,606.

To all whom it may concern:

Be it known that I, PHILIPP WIRTH, a citizen of the United States, residing at New York, in the county of New York and State 5 of New York, have invented new and useful Improvements in Filling-Faucets, of which the following is a specification.

This invention relates to a device for filling containers, such as barrels and casks, 10 and has particular application to an automatic faucet operable to cut off a supply of liquid or fluid when a predetermined quantity of the latter has been fed into the container.

15 In the present instance, it is my purpose to provide a filling faucet through which the liquid may pass, from a source of supply, into the container, and which faucet will operate under fluid pressure, such as 20 air, from within the container to automatically cut off the supply when the liquid has reached a certain height in the container. By my invention, the necessity of having an attendant carefully watch the filling operation to prevent the overflow, or spilling 25 and consequent waste of the liquid, is obviated, while considerable time, as well as labor, may be saved where a large number of casks or barrels are to be filled, because 30 a number of the faucets may be in use simultaneously on a corresponding number of barrels and all under charge of one attendant, as each individual faucet, being automatic in its cut-off operation, will not require personal 35 attention on the part of the operator to prevent overflow.

It is also my purpose to provide an automatically operating filling faucet of this type which will embody the desired features 40 of simplicity, efficiency, reliability and convenience, and which may be manufactured and marketed at a relatively low cost.

With the above recited objects and others of similar nature in view, my invention 45 consists in the construction, combination and arrangement of parts set forth in and falling within the scope of the appended claims.

In the accompanying drawings,

50 Figure 1 is a view in elevation of my improved faucet, showing the same in use, in connection with a barrel, a portion of the latter being broken away to show the

position of the lower part of the faucet relative to the interior of the barrel.

55

Fig. 2 is a view in end elevation of the faucet shown in Fig. 1.

Fig. 3 is a top, plan view, with a portion of one of the cap nuts broken away.

Fig. 4 is a view, partly in longitudinal 60 section and partly in elevation and showing the interior construction and arrangement of the faucet.

Fig. 5 is a sectional view taken on the line 5—5 of Fig. 4 and looking in the direction of the arrow.

Fig. 6 is a similar view taken on the line 6—6 of Fig. 4, the faucet being shown in this view as inserted in the bung-hole of the barrel.

70

Referring now to the accompanying drawings in detail, the letter A indicates conventionally a barrel, cask or other container, having the usual bung-hole a and within which the faucet is intended to be inserted.

75

My improved automatically operating cut-off faucet is indicated as an entirety by the letter B and embraces a casing 1 interiorly divided by the wall 2 into the valve chambers 3 and 4. Communicating with the 80 valve chamber 4 is a hollow coupling head 5, to which may be attached a flexible hose, or other fluid conduit, shown at 6, and from which the liquid passes from a source of supply into the faucet, this hose being fastened to the coupling head of any suitable coupling, such as is shown at 7. Preferably formed integral with and depending from the body of the casing 1, is the barrel 8 of the faucet, this barrel communicat- 90

ing through the valve passage-way 9 with the valve chamber 4. The upper portion 10 of the faucet barrel is tapered in form, and merges into the straight or cylindrical section 11, which forms the lower end sec- 95 tion of the barrel. The interior of the barrel is provided with a fluid passage, in the present instance, an air conduit or passage-way 12 which opens at its lower end through the wall of the cylindrical section 11 of 100 the barrel, as shown at 12, and at its upper end communicates through the channel or by-pass 14 with the lower portion of the valve chamber 3. Within the valve chamber 4 is located a disk valve 15 having a 105 beveled edge 16, so that the valve may seat

against the correspondingly tapered wall 17 of the passage 9 between the chamber 4 and the barrel of the faucet, as will be readily understood. The stem 18 of the valve slides 5 in the socket 19 of the screw cap 20, and which cap constitutes the top wall of the chamber 4. A suitable packing 21 may be employed to make the cap fluid-tight when screwed in place. The interior of the valve 10 chamber 3 is cylindrical in form and sliding therein is a cylindrical, hollow plunger 22 having a lower end wall 23 in the form of a perforated disk or head threaded into the end of the plunger, the perforations being 15 shown at 25. Likewise, the upper end wall of the plunger is shown at 26 and this wall is also perforated as at 27 and is formed with a hollow, central stud 28 projecting through the opening 29 in the center of the 20 screw cap 30, this latter cap forming the top wall of the chamber 3. A stem or handle 31 is threaded into the stud socket 28, so that the plunger may be lifted manually when desired, as hereinafter mentioned. A 25 horizontal web 32 extends across the interior of the hollow plunger and is formed with a central opening 33. A cage is thus formed in the lower part of the plunger for the ball valve 34 which is adapted to be 30 lifted by air pressure to close the passage 33, as will be hereinafter understood. The numeral 35 indicates a revoluble shaft finding bearing in the lower portion of the casting 1, the inner end of the shaft lying just 35 below the passage-way 9 between the barrel of the faucet and the chamber 4, this end of the shaft carrying a collar 36 provided with a valve lifting cam 37 which is adapted to lift and support the valve disk 15 at cer- 40 tain times. On that intermediate portion of the shaft, which lies in alignment with the chamber 3, is a collar 38 carrying the plunger lifting stem 39, which is adapted to support the plunger in elevated position 45 at predetermined times. The outer end of the rotating or rocking shaft 35 carries a counterweighted arm 40, the counterweight of the arm being practically in the form of a sphere and of heavy metal, such as is 50 shown at 41. The shaft is also made fluid-tight and held in position by suitable packing nuts and glands, as shown at 42. These packing nuts and glands 42 may be of any suitable and well known construction.

55 From the above description taken in connection with the accompanying drawings, the construction and operation of my automatic filling faucet will be readily understood. When it is to be used, the lower or 60 cylindrical end of the faucet barrel is inserted in the bung-hole until the tapered section of the barrel wedges against the tapered wall of the bung-hole, and in this position, the air opening 13, leading to the passage 12, 65 will communicate with the interior of the

barrel. The operator may now grasp the stem 31 and lift the plunger 22 within the chamber 2, at the same time grasping the counterweight 41 and swinging the arm 40 upward to the position shown in full lines in 70 Fig. 5. This will cause the rock shaft 35 to be turned, thus swinging the stem 39 upward within the chamber 3 and likewise swinging the cam 37 upward, and consequently lifting the valve disk 15 from its 75 seat, so as to open the passage 9 between the chamber 4 and the barrel of the faucet. The operator may now release his grasp upon the handle 31 and the plunger will settle down or drop back onto the stem 39, 80 holding, or pinning, the stem in its elevated position, and consequently holding the counterweight 41 elevated and likewise insuring that the valve 15 will be held open by the cam 37, as the shaft 35 is thus held stationary. The liquid may now flow through the hose 6, coupling 5, chamber 4, passage 9 and the barrel of the faucet into the container A. As the liquid continues to feed into the container, the air pressure within 90 the latter is gradually increased as the liquid displaces the air, until when the container is substantially full, or until the level of the liquid has about reached the air hole 13, the pressure of air will be so great that 95 as it is forced through the air passage 12 and by pass 14 into the chamber 4, it will pass up through the ports or apertures 25 in the lower end wall of the plunger, and will lift the ball valve 34, thus cutting off, or 100 closing, the opening 33 in the wall 32. When this opening is thus plugged by the ball valve, the continued pressure of the air will force the plunger upwardly, just a sufficient distance to lift it off the end of 105 the stem 39, which has been held elevated by the plunger, and the stem being thus released, the counterweight 41 will draw the arm 40 downward, thus rocking the shaft 35 and lowering the stem 39 and also the cam 110 37, the downward movement of the latter allowing the valve disk 15 to drop to its seat, thus closing the passage 9 between the chamber 4 and the barrel, and thereby shutting off the supply of liquid to the barrel. The 115 faucet may then be removed, and the bung inserted in the barrel, and the faucet may then be used for filling other barrels, as will be obvious.

While I have herein mentioned air as the 120 pressure exerting medium, it will, of course, be understood that the valve will operate equally well under pressure of other fluids, such as a liquid for example; and while I have herein shown and described one particular embodiment of my invention, I wish 125 it to be understood that I do not confine myself to all the precise details of construction herein set forth by way of illustration, as modification and variation may be made 130

without departing from the spirit of the invention or exceeding the scope of the appended claims.

What I claim is:

- 5 1. In a filling faucet for containers, a fluid conducting barrel adapted to be inserted within the container and communicating with a fluid inlet, a valve controlling the communication between the barrel and the inlet, a shaft carrying mechanism for engaging the valve to open it and for holding the valve in open position, and means adapted to operate under a predetermined fluid pressure from within the container to release the holding mechanism and permit the shaft to rotate to cause the closing of the valve.
- 10 2. In a filling faucet for containers, a fluid conducting barrel adapted to be inserted in the container and communicating with a fluid inlet, a valve controlling the communication between the barrel and the inlet, a shaft carrying mechanism for engaging the valve to hold it in open position, a device including mechanism mounted on the shaft and spaced from the valve holding mechanism, adapted for maintaining said shaft in said valve holding position, and means associated with said device and adapted to operate on the same under a predetermined fluid pressure to release the holding means, and permit the shaft to rotate to cause the closing of the valve.
- 15 3. In a filling faucet for containers, a fluid conducting barrel adapted to be inserted in the container and communicating with a fluid inlet, a valve controlling the communication between the barrel and the inlet, a shaft carrying mechanism for engaging the valve to hold it in open position, a device including mechanism mounted on the shaft and spaced from the valve holding mechanism, adapted for maintaining said shaft in such valve holding position, means associated with said device and adapted to operate on the same, under a predetermined air pressure from within the container, to release the holding mechanism, and gravity operating means connected with the shaft for moving the same to position to allow the closing of the valve.
- 20 4. In a filling faucet for containers, a fluid conducting barrel adapted to be inserted in the container and communicating with a fluid inlet, a valve controlling the communication between the barrel and the inlet, a shaft carrying mechanism for engaging the valve to hold it in open position, a device including mechanism mounted on the shaft and spaced from the valve holding mechanism, adapted for maintaining said shaft in such valve holding position, and means associated with said device and adapted to operate on the same under a predetermined air pressure to release the holding mechanism and permit the shaft to revolve to cause the closing of the valve.
- 25 5. In a filling faucet for containers, a fluid conducting barrel adapted to be inserted in the container and communicating with a fluid inlet, a valve controlling the communication between the barrel and the inlet, a shaft carrying mechanism for engaging the valve to hold it in open position, a device including mechanism mounted on the shaft and spaced from the valve holding mechanism, adapted for maintaining said shaft in such valve holding position, and means associated with said device and adapted to operate on the same, under a predetermined air pressure from within the container, to release the holding mechanism, and gravity operating means connected with the shaft for moving the same to position to allow the closing of the valve.
- 30 6. In a filling faucet for containers, a fluid conducting barrel adapted to be inserted in the container and communicating with a fluid inlet, a valve controlling the communication between the barrel and the inlet, a shaft carrying mechanism for engaging the valve to hold it in open position, a device including mechanism mounted on the shaft and spaced from the valve holding mechanism, adapted for maintaining said shaft in such valve holding position, and means associated with said device and adapted to operate on the same, under a predetermined air pressure from within the container, to release the holding mechanism, and gravity operating means connected with the shaft for moving the same to position to allow the closing of the valve.
- 35 7. In a filling faucet for containers, a fluid conducting barrel communicating with a fluid inlet, a valve controlling the communication between the barrel and the inlet, a chamber having a plunger moving therein, a rock shaft having a member adapted to engage the valve to move the same to open position and allow communication between the inlet and the barrel, a second member mounted on said shaft and projecting into the plunger chamber and adapted to be engaged by the plunger to hold the rock shaft stationary with the valve in open position, a pressure operated element carried by the plunger, means for conducting air pressure from the container through the barrel to the plunger, to operate upon said element and thus move the plunger, thereby releasing the shaft, and a weighted member for rocking said shaft to permit the closing of the valve.
- 40 8. In a filling faucet for containers, a casting having a pair of chambers, one of said chambers having a barrel and a fluid inlet communicating therewith, a valve member controlling the fluid inlet, a plunger work-

nism and permit the shaft to revolve to cause the closing of the valve.

5. In a filling faucet for containers, a fluid conducting barrel adapted to be inserted in a container and communicating with a fluid inlet, a valve controlling the communication between the barrel and the inlet, a rocking shaft adapted to be rocked to engage the valve and hold the same in open position, a shiftable device including mechanism mounted on the shaft and spaced from the valve holding mechanism, adapted for maintaining the rocking shaft in such valve-holding position, and a pressure operated member associated with said device and operable under a predetermined air pressure from within the container to shift said device, thereby releasing the valve holding member to permit the shaft to rock to cause the closing of the valve.

6. In a filling faucet for containers, a fluid conducting barrel adapted to be inserted in a container and communicating with a fluid inlet, a valve controlling the communication between the barrel and the inlet, a shaft carrying mechanism for engaging the valve to hold it in open position, a shiftable device including mechanism mounted on the shaft and spaced from the valve holding mechanism, adapted for maintaining said shaft in such valve holding position, means associated with said device and adapted to operate on the same, under a predetermined air pressure from within the container, to release the holding mechanism, and gravity operating means connected with the shaft for moving the same to position to allow the closing of the valve.

7. In a filling faucet for containers, a fluid conducting barrel communicating with a fluid inlet, a valve controlling the communication between the barrel and the inlet, a chamber having a plunger moving therein, a rock shaft having a member adapted to engage the valve to move the same to open position and allow communication between the inlet and the barrel, a second member mounted on said shaft and projecting into the plunger chamber and adapted to be engaged by the plunger to hold the rock shaft stationary with the valve in open position, a pressure operated element carried by the plunger, means for conducting air pressure from the container through the barrel to the plunger, to operate upon said element and thus move the plunger, thereby releasing the shaft, and a weighted member for rocking said shaft to permit the closing of the valve.

8. In a filling faucet for containers, a casting having a pair of chambers, one of said chambers having a barrel and a fluid inlet communicating therewith, a valve member controlling the fluid inlet, a plunger work-

- ing in the other chamber, a rock shaft journaled in the casing and having a member adapted to engage said valve to open the same, and having a second member adapted 5 to be engaged by the plunger when the valve is lifted by the first mentioned member, whereby said shaft will be held stationary with the valve in open position, an air conduit opening through the barrel and leading 10 into the plunger chamber, said plunger being movable when the air pressure reaches a predetermined degree, whereby to release the rock shaft, and a weight for operating said rock shaft to move the members away 15 from the valve and plunger respectively and permit the closing of the valve.
9. In a filling faucet for containers, a fluid conducting barrel adapted to be inserted within the container and having a 20 passage connecting it to a fluid inlet, a valve controlling the communication between the valve and the inlet, a chamber located adjacent said passage, a shaft extending into said chamber, means carried on the shaft for 25 moving said valve, and means contained in said chamber for holding the shaft and valve engaging means in predetermined position; said means being operated by fluid pressure in the container to release the shaft.
- 30 10. In a filling faucet for containers, a fluid conducting barrel adapted to be in-

serted within the container and communicating with a fluid inlet, a valve controlling the communication between the barrel and the inlet, means for holding the valve in 35 open position, a chamber adjacent the barrel and inlet, means mounted in said chamber for maintaining said valve holding means in operative position and operated by fluid pressure from the barrel to release said 40 valve holding means.

11. In a filling faucet for containers, a fluid conducting barrel adapted to be inserted within the container and communicating with the fluid inlet, a valve controlling the communication between the barrel and the inlet, a chamber located adjacent 45 said valve, a shaft extending into said chamber and into proximity to said valve, means mounted on the shaft for holding the 50 valve in open position, means located within the chamber for holding the shaft in position to maintain the valve open; said means including an extension mounted on said shaft and a catch mounted in said chamber 55 and released by fluid pressure from the container to permit the shaft to rotate and release the valve.

In testimony whereof I have hereinto set my hand.

PHILIPP WIRTH.
